UNITED STATES PATENT OFFICE.

WILLIAM H. BAILEY, OF CANAL DOVER, OHIO.

SPRING-BALANCE FOR METAL ROUGHING AND FINISHING MILLS.

SPECIFICATION forming part of Letters Patent No. 770,950, dated September 27, 1904.

Application filed September 27, 1902. Serial No. 125,086. (No model.)

To all whom it may concern:

Be it known that I, WILLIAM H. BAILEY, a citizen of the United States, residing at Canal Dover, in the county of Tuscarawas and State 5 of Ohio, have invented certain new and useful Improvements in Spring-Balances for Metal Roughing and Finishing Mills; and I do hereby declare the following to be a full, clear, and exact description of the invention, such 10 as will enable others skilled in the art to which it appertains to make and use the same, reference being had to the accompanying drawings, and to the letters of reference marked thereon, which form a part of this specification.

15 My invention relates to a "spring-balance for metal roughing and finishing mills" or means for automatically balancing and raising, also the steady and even lowering of the top roll of a mill when the screws are run up 20 or down the desired distance, so as to leave the necessary space between the rolls as required, according to the thickness of the bars of metal to be inserted between said rolls, and although more especially intended or 25 designed for service on metal roughing mills is also susceptible for use on various other mills or devices of a different character, but wherein the principles are similar.

The principal objects and advantages of 30 this invention consist in producing a device that will take the place of and be an improvement over the old method of raising the upper or top roll of a metal mill when the screws are run up, as heretofore. It then being cus- 35 tomary to employ the old style of lever-balance wherein a long lever and weights are used, said lever being placed in the pit under the rolls. This method is very objectionable, for the reason that there is considerable trou- 40 ble caused by the weights falling off and being down in the pit are difficult to handle. Besides they need constant attention; but my "spring-balance" needs no attention, as it works automatically, is effective in its results, 45 simple in construction, can be readily and easily handled and repaired, and is inexpensive in cost of manufacture.

My invention, referring in general terms to its construction, consists of the bridge and

its supports, the carrier and its bearing, and 50 suitable resilient or reacting means arranged to constantly and automatically force or act against the carrier and the peculiar and novel construction, combination, and arrangement of these parts, as will be described more 55 fully hereinafter and pointed out in the subjoined claims in accordance with the statutes in such case made and provided therefor.

Referring to the annexed drawings, forming 60 a part of this specification, and wherein the same letters of reference refer to like parts wherever they occur throughout the several views, Figure 1 is a view in end elevation of a pair of rolls and the housing for same and having my spring-balance in operative position, so as to show the practical application 65 of my invention. Fig. 2 is a side view of my spring-balance with the parts together ready to be placed in position between a pair of rolls. Fig. 3 is a perspective view in detail 70 of the carrier. Fig. 4 is a perspective view in detail of the bridge. Fig. 5 is a perspective view in detail, partially broken away and in section, of one end of the bridge, so as to show the construction when the supports are 75 formed integral and a part of the bridge, which may be done when desired; and Fig. 6 is a view in front elevation of a pair or set of rolls and the housings for same, partially 80 broken away and in section through the window of the housing at one end and taken on the line $y-y$ of Fig. 1, showing my spring-balance in operative position, so as to more 85 fully illustrate the practical application of my invention.

In describing my said invention and referring in detail to the different parts or mechanical elements of construction as shown throughout the various views of the drawings, and indicated by means of the letters of reference, as aforesaid, A refers to the carrier, preferably constructed out of cast-steel and provided with a bearing a , of brass or Babbitt metal, which bears up against and upon which rests the neck of the upper or top roll when 90 said carrier is in position, said carrier being further provided with lugs or projections b , adapted to rest and move in suitably-formed

recesses or grooves located in the inner face of the housings at each side of the windows, thus permitting of the carrier moving up and down as it forces said upper roll upward or 5 permits of said upper roll moving steadily and evenly downward, according to the direction in which the screws B are run, by reason of the action of the springs or reacting members C, which are retained in place in an 10 upright position by the small bearings d and e, projecting from carrier A and bridge F, respectively. Bridge F is preferably constructed out of cast-steel (the same as carrier A) and acts as a support for the carrier, as is 15 clearly shown in the drawings, particularly in Fig. 1, said bridge being in turn supported in a stationary position by lugs f, which may be placed or formed on the inside of the face of the housings, as shown in Fig. 1, or said 20 lugs may be separate from the housings and formed integral with the bridge and provided with openings or eyes g, adapted to receive screws, as shown in Fig. 5, the under side or face of said bridge being slightly concaved, as at h, thus leaving a space, as at i, 25 between it and the neck of the lower roll, which permits of oil, grease, or other lubricant being applied to the neck of said roll when found necessary, said bridge being 30 further provided with lugs l, adapted to rest in the recess or groove in the housings.

If desired, both the carrier and bridge may be suitably provided with a sufficient number of perforations to allow of water passing 35 through onto the neck of the rolls, thus cooling them.

It can be clearly understood and will be obvious from the foregoing description that my spring-balance is of course intended and designed to be inserted in the window of each 40 housing at both ends of the pair of rolls. It will act automatically and by reason of the springs or reacting members will permit of the upper roll working steady, even, and uniformly, will do away with all labor in raising 45 the upper roll, and being above ground and in plain view the condition of the device can be seen at all times, and, furthermore, my spring-balance can be manufactured and any

worn parts readily replaced at a very small 50 cost.

I wish it to be here understood that I reserve the right under the well-established principles of patent law to make any minor changes and alterations in the arrangement 55 and construction of the several parts of my device as may from time to time suggest themselves so long as within the scope and not departing from the spirit and principles of the 60 invention.

Having now described my spring-balance for metal roughing and finishing mills, I will proceed to point out what is new and my invention. Therefore

What I claim is—

1. In a rolling-mill, and in combination with the upper and lower rolls, of a carrier for the upper roll having a central bearing for said roll, end lugs fitted to slide in the frame of the mill, and projections upon the under face 70 of said carrier near the lugs, and a bridge having lugs fitted to slide in the frame of the mill, projections on the upper face of the bridge in line with the lugs on the carrier, and a central bearing for the lower roll, and 75 springs intermediate the carrier and bridge said springs being seated upon the projections of the carrier and bridge.

2. In a rolling-mill, the combination of the upper and lower rolls, a carrier for the upper 80 roll having a central bearing fitted therein, end lugs mounted to slide in the frame of the mill, projections upon the lower face of the carrier near the lugs, a bridge having a central bearing for the lower roll, lugs to slide 85 in the frame, projections upon its upper face in line with the projections on the carrier, springs interposed between the carrier and bridge and seated upon the projections of the carrier and bridge, lugs at the ends of the 90 bridge, and a screw for adjusting the rolls.

In testimony whereof I have affixed my signature in presence of two witnesses.

WILLIAM H. BAILEY.
